UNITED STATES PATENT OFFICE

ALBERT ALLEN, OF WINCHESTER, MASSACHUSETTS, ASSIGNOR, BY MESNE ASSIGNMENTS, TO ATLANTIC PRECISION INSTRUMENT COMPANY, OF BOSTON, MASSACHUSETTS, A CORPORATION OF MASSACHUSETTS

METHOD AND MEANS FOR MEASURING MATERIAL TAKEN UP BY A TREATED WEB

Application filed September 17, 1925, Serial No. 56,923. Renewed June 29, 1932.

This invention relates to a method and apparatus for measuring the amount of material picked up by a web, whether through absorption, surface coating, or both absorption and coating. More particularly the method and apparatus of this invention is applicable for measuring such material when the web is traveling so that variations in the amount of material picked up by different portions of the web treated are made immediately apparent, whereupon correctional factors may be availed of in time to render the amount of material taken up approximately uniform over extended lengths of web and during long treating periods.

Commercial examples to which this process and apparatus are applicable may be mentioned, such as in the treating of fabric with waterproofing agents, as rubber, the saturation or coating of paper felt with asphalt or other bituminous material for roofing or flooring purposes, the saturating and coating of fabric bases with linoleum or other compositions, and for various other purposes.

This measuring is accomplished in the present invention by measuring the running weight of the treated web material corrected for the running weight of the untreated web.

The measurement of the running weight of sheet material, whether the treated or untreated web, may be readily and accurately ascertained by the method and mechanism fully described and claimed in my application for Patent Serial No. 27,327, filed May 1, 1925, Patent No. 1,708,074, April 9, 1929, for indicating and controlling method and mechanism for paper making machines and the like, and in that application is also disclosed and claimed a method and mechanism by which the running weight of certain constituents only of the material may be measured, certain others (specifically disclosed as the moisture content) being eliminated. In the present case the same general method of procedure is followed out, the running weight of the foundation sheet material or web being that constituent of the treated sheet material which is eliminated so that determination of the weight of the treating agent alone is effected.

In general the method employed is that which comprises subjecting to the influence of the untreated and the treated web separate devices of the same character each having characteristics other than but dependent in value on the running weight of the particular material to the action of which they are subjected, and determining the amount of such characteristics of the device exposed to the influence of the treated web corrected for the amount of such characteristics due to the presence of the web foundation alone as measured by the other device, the final determination being calibrated in terms of the running weight of the treating material alone.

More specifically the method comprises passing the untreated web between a pair of spaced metal plates, treating the material and then passing the treated material between a similar pair of spaced metal plates, the two pairs of metal plates with the air and sheet material interposed therebetween comprising electrical condensers, the capacities of which vary with the amount of sheet material therebetween at any instant. The capacities of these condensers may then be read by suitable means in terms of the running weight of the material, and as one represents the total weight and the other the weight of the foundation or untreated web alone over the areas between the two pairs of blades, their difference is the running weight of the treating material alone.

A highly sensitive method for indicating changes in capacity between such condensers comprises employing the latter to tune an oscillatory pick-up circuit near to the resonance point of an exciting oscillatory circuit and measuring the current induced in the pick-up circuit, which is a maximum when the circuits are at resonance and decreases rapidly as the two circuits depart from resonance.

For a more complete understanding of this invention, reference may be had to the accompanying drawing illustrating diagrammatically an apparatus by which the measurement may be effected.

Referring to this drawing, the web *w* is shown as fed in the direction of the arrow 100

between a pair of electro-conductive plates 1 and 2 held fixedly and spaced sufficiently to permit the web to pass freely, the web thus forming part of the dielectric between these plates. After passing between these plates it passes to a suitable treating mechanism by which the material with which it is to be treated is applied thereto.

While the particular type of treating mechanism may depend on the nature of the web and of the material to be applied and also on the purpose for which this application is intended, it is herein shown diagrammatically and for the purpose of illustration only as a tank 5 for containing a treating liquid. The web after passing between the plates 1 and 2 is shown as passing over a roller 6 and then down beneath the surface of treating liquid in the tank 5 about a pair of rollers 7 and 8 and then upwardly out of the treating tank and between a pair of squeeze rollers 9 and 10 by which if desired the material may be fed. These squeeze rollers may, if desired, be adjustable so that they may have an effect to control the amount of treating material which is retained by the web. Any other means which might be found suitable in the particular instance, of course, might be adopted for this purpose. After passing between these squeeze rollers the web passes between the spaced metal plates 15 and 16 which together with the treated web passing therebetween constitute a second electrical condenser. These plates 15 and 16 are held fixedly and spaced sufficiently to permit the treated web to pass between them freely.

At A is indicated diagrammatically a well-known form of high frequency oscillatory electric circuit. Any suitable oscillating circuit which should for best results be as stable as possible may be employed. As shown that employed is that of a low powered radio transmitter comprising a transmitting tube 40 20, a filament or A battery 21 and a plate or B battery 22, the plate circuit being tuned through an inductance 23 and a condenser 24 which may be variable for adjusting purposes. At 25 is shown a coil in inductive relation to the coil 23 which is connected through a grid leak 26 with the tube grid 27. A resistance 28 is inserted adjacent to the B battery 22 as a protection device, and this is shunted by means of a condenser 29 to provide a by-pass for high frequency currents. The plates 1 and 2 are shunted about the condenser 24 of the oscillatory sending or exciting circuit, and with the treated web 50 therebetween constitute a tuning element variable with changes in running weight of the treated web. This transmitter may be shielded as through a grounded shield 30 and extending outwardly of the shield is a loop 31 forming a continuation of the coil 23,

and with which the receiving or pick-up circuit B is loosely coupled.

The pick-up circuit comprises a coil 32 which receives the waves from the loop 31 and across this coil are shunted the variable tuning condensers 33 and 34, one of these being a Vernier condenser in order that fine tuning may be accomplished. Shunted about the condensers 33 and 34 are the condenser plates 15 and 16 and coupled in any suitable manner, as by the transformer coils 35 and 36, is a thermo-galvanometer or other current indicating instrument as at 40.

Assuming now a suitable constant frequency in the sending circuit A, and a constant capacity of the condenser comprising plates 1 and 2 and elements therebetween, the receiving circuit B may be tuned to resonance therewith and when this is accomplished the current flow through the receiving circuit B is a maximum, reading on the thermo-galvanometer 40. Any variation of the capacity of the condenser formed by the plates 15 and 16 due to change in the weight of the treated web will cause the receiving circuit B to be thrown out of resonance with the sending circuit A so that the current flow through the receiving circuit will be decreased and a corresponding indication given on the instrument 40. The receiving circuit may then be brought up to resonance, if desired, by varying the capacities of the condensers 33 and 34, such change evidently being a measure of the change of capacity of plates 15 and 16 with the interposed web because of change of mass of the treated web.

Changes of capacity of the condenser comprising the plates 15 and 16 and the interposed treated web are due to changes in running weight of the treated web which includes the web itself as well as the treating material picked up during its treatment, and might be due in part to variations in the weight of the web alone. Variations in the weight of the web, however, are taken care of by the condenser comprising the plates 1 and 2 between which the untreated web passes, any variation in the weight of the untreated web acting to change the tuning of the oscillatory sending circuit, so that by proper adjustment a tuning effect due to the running weight of the untreated web may be caused to oppose the tuning effect of the same web after it has been treated and as it passes between the condenser plates 15 and 16, so that the variations from resonance between the oscillatory sending and pick-up circuits may be caused entirely by variations in the running weight of the treating material which is picked up by the web.

While the pick-up circuit may be adjusted to be in resonance with the sending circuit so that readings of the instrument 40 are maintained at a maximum, this being done

by adjustment of the condensers 33 and 34, if the pick-up circuit is maintained at one side of the resonance point with relation to the sending circuit the changes in current reading then become a direct indication of the changes in capacity due entirely to the treating material picked up by the web.

It is therefore seen that if other conditions are held constant the instrument 40 may be calibrated directly in terms of the running weight of the treating material picked up by the web, or the dials of the condensers 33 and 34 may be calibrated directly in such running weights, the reading of the thermo-galvanometer 40 being held at the maximum point.

From the foregoing description of an embodiment of this invention, it should be evident that various changes and modifications might be made therein without departing from the spirit or scope of this invention as defined by the appended claims.

I claim:

1. The method of measuring the amount of material taken up by a traveling web treated with such material, which comprises measuring in terms of the running weight of such material electrical characteristics due to the web and material taken up thereby diminished by the amount of such characteristics due to the web alone.

2. The method of determining the amount of material taken up by a web treated with such material, which comprises passing the untreated web between a pair of spaced electro-conducting elements, treating said web with such material, passing the treated web between a second pair of spaced electro-conducting elements, and continuously indicating in terms of the weight of the treating material taken up by said web the capacity of said second pair of conducting elements and interposed treated web corrected for the running weight of said web by the capacity of said first pair of conducting elements and interposed untreated web.

3. The method of measuring the amount of material taken up by a traveling web treated with such material, which comprises passing such web before treatment between one pair of spaced electro-conducting plates and after treatment between a second pair of electro-conducting plates, tuning an exciting oscillatory electric circuit by the capacity of said first plates and interposed untreated web, and tuning a pick-up circuit by the capacity of said second pair of plates and interposed treated web near resonance with said oscillatory circuit, and measuring the induced current in said pick-up circuit in terms of the running weight of material picked up by said web.

4. An apparatus of the class described comprising means for feeding a web of material to be treated, one pair of spaced elec-

tro-conducting plates between which said web passes, means for treating the web with material, a second pair of spaced electro-conducting plates between which said treated web passes, an exciting oscillatory electrical circuit tuned by said first pair of plates and interposed treated web, a pick-up circuit tuned to near resonance with said oscillatory circuit by said second pair of plates and interposed treated web, and means for measuring the current flow in said pick-up circuit.

5. The method of measuring the amount of material taken up by a web treated with such material, which comprises measuring in terms of the weight of such material electrical characteristics due to the web and material taken up thereby diminished by the amount of such characteristic due to the web alone.

6. The method of determining the amount of material taken up by a web treated with such material, which comprises inserting untreated web material between a pair of spaced electro-conducting elements, inserting treated web material between a second pair of spaced electro-conducting elements, and indicating in terms of the weight of said treated web the capacity of said second pair of conducting elements and interposed treated web corrected for the weight of web alone by the capacity of said first pair of conducting elements and interposed untreated web.

7. The method of measuring the amount of material taken up by a web treated with such material, which comprises measuring in terms of such amount other characteristics of the treated web dependent on such amount diminished by the said other characteristics of the web alone.

8. The method of measuring the amount of material taken up by a web treated with such material, which comprises measuring in terms of such amount electrical characteristics of the treated web diminished by the same characteristics of the web alone.

9. The method of measuring the amount of material taken up by a web treated with such material, which comprises measuring the difference of dielectric capacity of certain areas of said web before and after being treated.

10. The method of measuring the amount of material taken up by a traveling web, which comprises continuously indicating in terms of such amount the difference between the dielectric capacities of successive areas of said web before and after its treatment by such material.

11. An apparatus of the class described, comprising means for feeding a web of material to be treated, a pair of spaced electro-conductive plates between which said web passes, means for treating the web with material, a second pair of spaced electro-con-

ductive plates between which said treated web passes, two oscillatory electric circuits each tuned by one of said pairs of plates and interposed web and near to resonance with each other, and means responsive to their nearness to resonance for indicating the weight of material taken up by said web.

12. An apparatus of the class described comprising means for feeding a web of material to be treated, one pair of spaced electroconductive plates between which said web passes, means for treating the web with material, a second pair of spaced electroconductive plates between which said treated web passes, an exciting oscillatory electric circuit tuned by one of said pair of plates and interposed web, a pick-up circuit tuned to near resonance with said exciting circuit by the other pair of plates and interposed web, and means for measuring the current flow in said pick-up circuit induced by said exciting circuit.

13. An apparatus of the class described comprising means for feeding a web to be treated, a pair of spaced electroconductive plates between which said web passes, means for treating said web with material, a second pair of spaced electroconductive plates between which said treated web passes, and means responsive to the capacities of said two pairs of plates and interposed web for indicating the amount of material taken up by said web.

In testimony whereof I have affixed my signature.

ALBERT ALLEN.
